UNITED STATES PATENT OFFICE

2,086,641

ELECTRICAL CONNECTER

Lee Hunter Riley, University City, Mo.

Application March 26, 1936, Serial No. 69,810

3 Claims. (Cl. 173—332)

My invention relates to electrical connectors for general use, including use in outlet boxes and as a plug member for lamps and other devices and their source of electric current.

5 The invention has as its principal object a connector that is simple, sturdy and inexpensive, that is neat and inconspicuous in appearance, that avoids the danger of electrical shocks, that minimize the risk of fraying or breaking the electric wiring and that has other important practical advantages.

The invention consists principally in an electrical connector comprising box-like members, each having spaced terminals for receiving the 15 ends of the two wires of an electric cord and spaced conductor members having portions cooperating with said terminal members and having projecting portions adapted to fit into the spaces between the respective pairs of terminal and conductor members of the other box. The invention further consists in the electrical connector and in the parts and combinations and arrangements of parts hereinafter described and claimed.

In the accompanying drawing, 25 Fig. 1 is an elevation of an electric lamp provided with an electrical connector embodying my invention.

Fig. 2 is a side elevation of the two portions of the connector member.

30 Fig. 3 is a bottom plan, with portions broken away, looking in the direction of the arrows 3—3 in Fig. 2, showing the upper box portion of the connector.

Fig. 4 is a top plan looking in the direction of 35 the arrows 4—4 of the lower box member.

Fig. 5 is a longitudinal sectional view of the two box members in spaced, superimposed relation, ready for assembly.

Fig. 6 is a similar view of the assembled connector.

Fig. 7 is a detail view of one of the terminal members, and

Fig. 8 is a sectional view on the line 8—8 of Fig. 7.

45 In Fig. 1 is illustrated an electric lamp L having secured in the base 1 thereof the upper box portion 2 of an electrical connector member C embodying my invention, the lamp wiring cord 3 running from said box portion 2 through the lamp standard 4 to the light socket members 5. The box 1 may be secured to the base by molding or casting it directly therein or by means of screws extending through holes 2a provided therefor in the box. The lower or cooperating 50 box portion 6 of the connector is secured to the

end of an electric extension cord 7 whose other end is connected with a suitable outlet 8. This outlet may be a connector embodying the present invention, but is illustrated as being a connector of the kind shown in my co-pending patent application. 5

The cooperating box members 2 and 6 are preferably made of a suitable plastic, as a resin, or some other suitable composition and are provided with cover plates 9 secured thereto as by screws 10 10.

The upper box member 2 may be secured to a lamp or other electrical device and has terminal members 11 mounted against the underside of its top 12, as by mean of ears 13 embedded therein. 15 The box member 2 is provided with an opening for the electric cord 7 or the two wires 14 thereof and each wire 14 has the end thereof secured to one of said terminals 11. The terminal construction illustrated includes a binding post 15 20 having an opening 16 to receive the end of a wire 14 and a screw 17 threaded into said binding post 15 for maintaining electrical contact with said wire. Each terminal member has an upstanding, slightly inclined contact tongue 18 that has 25 its tip portion 19 reversely bent with respect to the body of the tongue.

Arranged in cooperative relation to each of the terminal members 11 is an electrical conductor member 20 secured to the top of the box, as by 30 ears 21 embedded therein and having an upstanding contact tongue 22 that inclines toward the contact tongue 18 of the adjacent terminal member 11 and that has a reversely bent tip portion 23. The cover plate 9 is provided with openings 24 over the spaces between the contact tongues 22 and 18. Each conductor member also has an elongated contact arm 25 that projects through an opening 26 provided therefor in the cover plate 9 and that has a portion 27 rebent and preferably extending back through said opening 26 into the box member 2. 35 40

The lower box member 6 of the connector C, which is shown as having an opening for the end of the extension cord 7 has terminal members 28, similar to those 11 of the upper box 2, mounted therein as by means of ears 29 embedded in the bottom of the box and having upstanding contact tongues 30 with reversely bent tip portions 31. The ends of the wires of the 45 50 cord 7 are secured to said terminals. Said lower box member likewise has a conductor member 32 in cooperative relation with each of said terminal members 28, including contact tongues 33 with reversely bent tip portions 34 and upstand- 55

ing contact arms 35 extending through openings 36 provided in the cover plate and having their end portions 37 rebent and projecting back into the box. The cover plate also has openings 38 over the spaces between the contact tongues 30 and 33.

As appears from Figs. 5 and 6, the box members are assembled by bringing them into such position that the projecting arms 25 and 35, respectively, of each member are in alinement with the holes over the openings between the pairs of contact tongues of the other member and the two parts are then forced against each other. Obviously, the contact arms 25, 35 extend into the spaces between pairs of contact tongues and as all of the arms and tongues are of resilient metal, there will not only be a firm and gapless electrical contact at all points, but the two box members will be securely held together.

20 Preferably, the lower box member 6 will have its edge portion 39 rabbeted and the lower marginal portion of the upper box member will be in the form of a rib 40 extending into said rabbeted portion and making a neat joint between the two box members. All corners of the boxes may be rounded and one or both of the box members may be provided with side depressions 41 to form a suitable grip for use when handling the box member.

30 The above described construction has numerous advantages. The projecting conductor members are dead except when in contact with the spaced tongues, so that there is no danger of an electrical shock while assembling the two parts 35 of the connector. There is no strain on the wiring and the separation of the box members is without risk of damaging the wiring or breaking the connection between the wiring and terminal members. The electrical contact is positive and 40 certain by reason of the resilient engagement between the conductor arms and the contact tongues. The construction adapts itself to connection at the base of a lamp or other electrical device, thus avoiding the use of a cord dangling 45 from the device. The changing of cords is facilitated and a cord of the length desired at any place may be used, instead of having excess cords with their attendant unsightliness and danger. Obviously, the construction admits of considerable modification in the sizes and proportions of 50 parts and in the uses to which it is put, so that I do not wish to be limited to the precise construction shown.

What I claim is:

1. An electrical connector comprising opposed box members having cover plates for their opposed faces and having openings for electric wiring, terminal members in each box, the end of one wire being secured to each of said terminals, conductor members in each box for cooperation with said terminal members, said conductor members having contact arms projecting through holes provided therefor in said cover plates, said contact arms being angularly rebent and having their ends reentrant into the box through said holes, said conductor members and said terminal members having upstanding tongues inclined towards each other but with reversely bent tips 10 forming a flaring mouth, and the cover plates having openings over the several pairs of tongues, whereby an electrical circuit is established by placing the boxes with the contact arms of each box projecting into the spaces between the 20 tongues of the other box.

2. An electrical connector comprising opposed box members having cover plates for their opposed faces and having openings for electric wiring, terminal members in each box, the end of one wire being secured to each of said terminals, conductor members in each box for cooperation with said terminal members, said conductor members having contact arms of springy metal projecting through holes provided therefor in 30 said cover plates and having angularly rebent portions reentrant into said box through said holes, said conductor members and said terminal members having upstanding tongues of springy metal and the cover plates having openings over 35 the several pairs of tongues, whereby an electrical circuit is established by placing the boxes with the contact arms of each box projecting into the spaces between the tongues of the other box.

3. An electrical connector, double wires comprising opposed box members, terminal members in each box, the end of each wire being secured to one of said terminals, conductor members in each box, each conductor member cooperating with but spaced from one of said terminal members, 45 said conductor members having projecting contact arms, said conductor members and said terminal members having upstanding tongues, whereby an electrical circuit is established by placing the boxes with the contact arms of each 50 box projecting into the spaces between the tongues of the other box.

CERTIFICATE OF CORRECTION.

Patent No. 2,086,641.

July 13, 1937.

LEE HUNTER RILEY.

It is hereby certified that error appears in the printed specification of the above numbered patent requiring correction as follows: Page 1, second column, line 6, after the syllable "cation" and before the period insert the comma and words, No. 69,811 filed March 20, 1936; line 15, for "mean" read means; page 2, second column, line 40, claim 3, after "connecter" strike out the comma and insert instead the word "for"; and that the said Letters Patent should be read with these corrections therein that the same may conform to the record of the case in the Patent Office.

Signed and sealed this 19th day of October, A. D. 1937.
